NORMALIZING FURNACE

Clarence B. Hoak, Steubenville, Ohio

Application October 1, 1936, Serial No. 103,595

2 Claims. (Cl. 266—3)

The present invention appertains to new and useful improvements in means for treating sheet steel and like material to prevent oxidation and the formation of scales thereon as it is heated 5 and cooled in the furnace.

The principal object of the present invention is to provide a furnace of the character stated for normalizing sheet metal wherein the sheet metal is forced to pass through a non-explosive 10 gas as it is heated and then gradually cooled so as to prevent any form of oxidation.

Another important object of the invention is to provide a normalizing furnace wherein the sheet metal can be gradually cooled to any varying 15 degree desired.

Various other important objects and advantages of the invention will become apparent to the reader of the following specification.

In the drawings:—

20 Figure 1 represents a side elevational view of the furnace.

Figure 2 is a vertical sectional view on line 2—2 of Figure 3.

25 Figure 3 represents a longitudinal vertical sectional view through the furnace.

Figure 4 is a fragmentary side elevational view disclosing one of the air outlet ports with the shutter in partly open position.

Referring to the drawings wherein like numerals 30 designate like parts it can be seen that the furnace is elongated and of any extent desired, the same preferably being of oblong shape and having the wall construction 5 consisting of the liner 6, covering 7 and the insulating filler 8.

35 Reference characters A—B represent the end walls of the furnace through which the neck portions C—D of the end drum 9 extends. This drum 9 is of rectangular cross section and extends longitudinally through the furnace abutting 40 the ends thereof at its end and having a reduced intermediate portion 10 following the edge portions of the opening through the partition 11 defining an opening 13 between the heating chamber 14 of the drum and the cooling chamber 15.

Around the heating chamber 14 are set the L-shaped heating tubes 16 in the lower end portion of which is located a regular fuel or gas burner 17.

50 The upper ends of these tubes 16 extend through the top of the furnace and connect to a manifold pipe 18 which has a motor driven suction fan 19 at one end thereof. The upper portions of the tubes 16 are provided with butterfly valves 20 therein so that heat can be retained

in these tubes by maintaining the valve closed or partly closed. Less heat is of course retained if the valves are opened to allow a substantially full draft.

Inverted L-shaped tubes 21 alternate with the tubes 16 adjacent the heating compartment 14, the vertical portions of which depend to connect with the manifold 22 which is provided with a motor driven suction fan 23 at one end thereof.

The upper ends of the tubes 21 extend through the rear side of the furnace wall and are open to the atmosphere. Obviously the heat of the chamber 14 can be accurately gauged by regulating the heat valves 20 at the upper ends of the tubes 16.

Around the chamber 15 are the L-shaped air tubes 25—26 which are arranged in the same manner as the tubes 16—21 around the chamber 14. However, the tubes 25—26 are both used for air, the lower ends of the tubes 25 communicating with the manifold 27 which has the motor driven suction fan 28 at one end thereof, while the upper ends of the tubes 26 pass thru the top of the furnace and connect to the manifold 29 which has the motor driven suction fan 30 at one end thereof.

Obviously air passed through the tube 25 can be regulated by the pivotal shutters 31 on the upper ends thereof.

At each end of the furnace is located a water box 32 which may contain water or some other suitable liquid immersed in which are located the rollers 33 and 34 at the lower end of the corresponding neck C or D. The metallic strip 35 to be treated passes over the roller 36 on the upper edge of the box 32 and also between the rollers 33—34 in the liquid, and then over a roller 37 located in the horizontal portions of each of the necks C—D.

The interior of the drum 9 is charged with a protective gas through the inlet tube 38, which gas passes along the metallic sheet in a direction opposite to the direction of travel of the sheet. For keeping this gas in circulation a return pipe 39 extends from the neck D, toward the opposite end of the furnace and beneath the furnace to the other end thereof to communicate with the fan housing 40 in which the suction fan 41 operates. The conductor pipe 42 extends from the housing 40 into the drum 9 at the compartment 15. Thus the gas which is supplied to the drum is kept in circulation constantly. A water jacket 43 is provided around the return pipe 39 and has a water inlet pipe 44 and a water outlet pipe 45.

While the foregoing specification sets forth the

Invention in specific terms, it is to be understood that numerous changes in the shape, size and materials may be resorted to without departing from the spirit and scope of the invention as 5 claimed hereinafter.

Having thus described the invention what is claimed is:—

1. A furnace of the character described comprising an elongated hollow structure, a drum extending longitudinally in the hollow structure, a work traveling passageway through the drum, a protective gas inlet for the drum and means for circulating the gas through the drum, said drum being divided into a heating chamber and a cooling chamber through both of which the work passes, said heating chamber being provided with tubes extending adjacent the same, certain of said tubes having cold air passing there-
- 10
- 15

through and burners positioned in the remaining tubes for producing hot air.

2. A furnace of the character described comprising an elongated hollow structure, a drum extending longitudinally in the hollow structure, 5 a work traveling passageway through the drum, a protective gas inlet for the drum and means for circulating the gas through the drum, said drum being divided into a heating chamber and a cooling chamber through both of which the work passes, said heating chamber being provided with tubes extending adjacent the same, certain of 10 said tubes having cold air passing therethrough and burners positioned in the remaining tubes for producing hot air, and cold air tubes extending 15 adjacent the cooling chamber of the drum.

CLARENCE B. HOAK.
